WINDOW SHADE ATTACHMENT

John B. Probst, Cheviot, Ohio, assignor to Clopay Corporation, Cincinnati, Ohio, a corporation of Maryland

Application March 31, 1950, Serial No. 153,114

2 Claims. (Cl. 160—400)

1.

This invention relates to window shades, particularly those formed from vinyl plastic or like materials and is particularly concerned with the assembly of a shade of this type with a window shade roller or with a fibre board core.

Window shades formed from vinyl plastic material have recently been introduced on the market and have met with excellent commercial acceptance. The material is pleasing in appearance, sufficiently opaque, and hangs well when extended across a window opening. However, there are some disadvantages connected with its use and this invention is directed toward the problem of correcting certain of these objectionable features.

In attaching a plastic shade to a conventional wooden roller, it is not advisable to use tacks or staples because the material has some tendency to split or tear from the attachment holes and because the attachment bond so formed is not nearly as strong as that formed by a continuous line of adhesive. However, not all adhesives operate efficiently because adhesives of the type which include animal glue are not effective in maintaining a bond between a synthetic material such as vinyl plastic and wood or even fibre board, a material from which shade rollers are frequently made.

An even greater objection to the use of tacks is that the vinyl plastic material has the characteristic of having imparted to it imperfections in any surface which it contacts. Accordingly, if the shade is secured directly to the roller along a line of security, by tacks or staples, the entire shade will have imparted to its surface the tack or staple markings and to a lesser extent all of the imperfections and lines of roughening on the surface of the roller. It is difficult, if not impossible, to eliminate these imperfections once they have been imparted to the shade and, resultantly, when a shade secured in this manner is rolled tightly on a roller, it quickly develops a marred and unsightly appearance.

Having in mind the solution of these problems, one of the objects of the present invention has been to secure a window shade formed from vinyl plastic or like material to a conventional roller by an adhesive strip, one edge of which engages the shade and the other edge of which engages the roller, thereby providing independent security to the strip of both the shade and the roller.

Another object has been to secure a window shade formed from vinyl plastic or like material to a roller by means of an adhesive strip, the shade being secured to the strip by a resinous ad-

hesive of the type particularly adapted to form a bond between vinyl plastic and paper and the roller being secured to the strip by a different type of adhesive, preferably one which may readily be activated by the application of water such as for example an adhesive having a base of animal glue.

Another object of the invention has been to secure a window shade formed from vinyl plastic or like material to a shade roller by means of an adhesive strip having a backing of comparatively heavy paper such as kraft, the strip having a width substantially equal to the circumference of the roller so that the vinyl plastic shade is protected from the roller by the strip and that portion of the shade which is readily visible when the shade is extended in a window opening does not at any time contact directly the roughened surface of the roller and have imparted to it the imperfections conventionally present on such surface.

Another object of the invention has been to adapt the principles thereof to use with the assembly of what might be termed a replacement shade combination, or in other words, a shade which has been coiled around a hollow core rather than a roller and is sold for attachment to an existing roller.

Other and further objects of the invention will be apparent from the further and more detailed description of a preferred embodiment thereof when considered in conjunction with the drawings illustrating such an embodiment and in which:

35. Figure 1 is an elevational view of a shade and roller combination with the shade secured to the roller and in extended position.

Figure 2 is a sectional view along the line 2—2, Figure 1.

40. Figure 3 is a similar sectional view except that in this instance the shade has been wound partly onto the roller.

Figure 4 is an enlarged elevational view partially broken away illustrating the preferred form of independent attachment of the shade and roller to the adhesive strip.

Figure 5 is an elevational view of a replacement shade wound on a core and secured thereto in accordance with the invention.

50. Figure 6 is an elevational view illustrating the attachment of the replacement shade to the adhesive strip and in particular the adhesive which is adapted to secure the strip to the core.

55. Figure 7 is a view similar to Figure 6 except

that in this instance the adhesive strip shown in Figure 6 has been secured to the core.

Figure 8 is a cross sectional view of the replacement shade structure taken on the line 8—8, Figure 7.

Referring again to the drawings and particularly Figures 1 and 4, the shade and roller combination therein illustrated has been designated generally as 10. The shade proper indicated at 11 is preferably formed from vinyl plastic, and the roller indicated at 12 may be of any conventional type. The roller may include end closure caps 13 and pins 14 for positioning the roller on brackets. The shade has a conventional hem 15. The adhesive strip which is secured independently to both the shade and the roller has been designated 16.

The invention is best appreciated from a consideration of Figure 4 in which an extended edge portion of the vinyl plastic shade has been given the number 17. As shown, this is secured to an extended edge 18 of the adhesive strip 16 by a line of adhesive 19. This adhesive is preferably of a type containing a vinyl resin plasticizer and ketone solvents which is particularly effective in securing vinyl plastic sheet material to paper although it possesses certain disadvantages including the difficulty of reactivation which would render it ineffective for many adhesive purposes. The roller 12 is secured to the opposite extended edge 20 of the adhesive strip by a line of adhesive 21 which is preferably an adhesive which is readily subject to reactivation upon the application of water such as one having a base of animal glue.

It will be noted that the width of the adhesive strip 16 is substantially equal to the circumference of the roller 12 as shown in Figure 2 so that after the roller and shade have been secured to the strip in the manner illustrated, the portion of the shade which depends below the lower edge of the adhesive strip 16 and which is the portion that is particularly visible when the shade is in extended position in a window opening will be protected from the roller by the adhesive strip and will not at any time contact directly the outer surfaces of the roller and have imparted to it the imperfections present on such surfaces.

The application of the invention to a replacement shade assembly is illustrated in Figures 5-8 in which 23 represents a hollow core on which the shade 22 has been wound. It is a characteristic of vinyl plastic shades that when sold for replacement, they cannot effectively be wound on themselves but must be wound on some sort of core as the material lacks sufficient rigidity to be handled conveniently otherwise. Since the core is disposable, it is preferable to use the cheapest possible construction which will be effective for the purpose. Fibre board cores formed from spirally wound light weight material have been found to be very satisfactory, but when used with a vinyl plastic shade, the spiral markings will be imparted to the surface unless some means is provided for spacing the shade proper from the core surface.

The replacement shade as illustrated embodies the same general construction previously described except that the securance of the adhesive strip 16 to the roller is preferably accomplished by a spot reactivation of portions only of the adhesive strip 20, these portions being designated as 24, Figure 6. The purpose of this is to facilitate the removal of the replacement shade from the core 23 when it is desired to affix it to an

existing roller. At this time a securance is made along the entire length of the adhesive strip 20 in the same manner as illustrated in Figure 4.

The invention has a particular advantage in its application to shades of the type which are conventionally assembled by the householder. The securance between the shade and the adhesive strip is preferably performed by the manufacturer. The shade with the strip secured thereto may then be wound on a core and sold as a replacement shade or it may be secured to the roller and sold as a complete assembly in instances where the customer desires a roller. The attachment of the strip to the roller is a very simple operation which can be performed by the customer without difficulty.

While the invention is particularly directed to shades formed of vinyl plastic material, it also has application to shades formed from similar types of material having a surface which is readily marred by imperfections on the surface of the roller. Various different types of adhesive may be used in attaching the shade to the strip but the preferred type is one which may be effectively used with synthetic materials such as vinyl plastic and one which is not readily subject to reactivation by the application of water. It is highly preferable that the adhesive used to secure the strip to the roller be readily subject to water reactivation as this attachment will frequently be performed by the customer in his home.

Having described my invention, I claim:

1. In combination with a window shade formed from vinyl plastic sheet material and a shade roller, means for securing the shade to the roller comprising an adhesive strip formed of paper and having a substantial width dimension, the adhesive strip having a band of water insensitive plasticized adhesive deposited along one longitudinal edge thereof, said band securing the edge of the adhesive strip permanently to the upper transverse edge of the shade with a portion of the adhesive strip extending beyond the upper edge of the shade, the extended portion of the adhesive strip having a second adhesive band of water sensitive adhesive deposited along its longitudinal edge, said second band being parallel with and spaced from the first band, the spacing of said bands delineating a relatively narrow flexible uncoated strip area intervening between the two bands, the second band of adhesive adapted to be reactivated by water and secured adhesively upon the periphery of the shade roller whereby the upper edge of the shade is spaced from the roller by said relatively flexible uncoated strip area.
2. A replacement shade unit adapted to be adhesively secured upon a shade roller, said shade unit comprising a cylindrical core formed of fibrous material, a shade formed from vinyl plastic sheet material, an adhesive strip for securing the shade to the core, said strip formed of paper and having a substantial width dimension, the adhesive strip having a band of water insensitive plasticized adhesive deposited along one longitudinal edge thereof, said band securing the edge of the adhesive strip permanently to the transverse edge of the shade with a portion of the adhesive strip extending beyond the upper edge of the shade, the extended portion of the adhesive strip having a second adhesive band of water sensitive adhesive deposited along its longitudinal edge, said second band being parallel with and spaced from the first band, the spacing

of said bands delineating a relatively narrow flexible uncoated strip area intervening between the two bands, the second band of adhesive being separably secured upon the periphery of the core and adapted to be stripped therefrom and being adapted to be reactivated by water and secured adhesively upon the periphery of a shade roller whereby the upper edge of the shade is joined along a continuous line to the roller by said relatively flexible uncoated strip area.
